UNITED STATES PATENT OFFICE.

CHARLES A. HATCH, OF HARTFORD, CONNECTICUT.

WATER-ALARM FOR BOILERS.

SPECIFICATION forming part of Letters Patent No. 515,827, dated March 6, 1894.

Application filed March 23, 1893. Serial No. 467,284. (No model.)

To all whom it may concern:

Be it known that I, CHARLES A. HATCH, of Hartford, in the county of Hartford and State of Connecticut, have invented certain new and useful Improvements in Water-Alarms for Boilers, of which the following is a full, clear, and exact description, whereby any one skilled in the art can make and use the same.

The object of my invention is to provide a device that may be attached to a steam boiler and by means of which an alarm shall be automatically sounded when the water in the boiler rises or lowers beyond the high or low water level, the alarm being sounded either at a point near the boiler or at a point at any desired distance therefrom.

To this end my invention consists in the details of the several parts making up the apparatus as a whole and in the combination of such parts, as more particularly hereinafter described and pointed out in the claims.

Referring to the drawings: Figure 1 is a detail view in longitudinal section through the device showing my improvement. Fig. 2 is a detail view in cross section through the device at the upper part thereof and on a plane at right angles to the section of Fig. 1.

In the accompanying drawings the letter *a* denotes a tubular casing provided at its lower and upper ends with suitable means for connection to a steam boiler, and within the case *a* depending from each end of a pivoted lever *c* are supported the baskets *b* in the line of vertical movement of a float or buoy *d* located within the casing. The case is also provided at its lower end with a petcock *a'* serving as a blow-out or cleaning device, the upper and lower ends being formed of removable caps.

All of the parts above described are old, and, of themselves, form no part of my invention.

On the cap at the upper end of the case *a* is removably supported a whistle *e*, a passage *e'* extending from the tubular casing to the whistle. Between the whistle and the casing is located a stop cock *f* adapted to open or close the passage *e'* between the whistle and casing. There is secured to the underside of the upper end of the casing a fulcrum *g* to which is pivoted, preferably between the center and one end, the lever *c* supporting the

baskets *b*. There is also secured to the lever about midway of its length a valve *h* adapted to open or close the passage *e'* to the steam whistle.

On the end of the casing *a* is secured a binding post *i* that projects downward into the cap, being insulated at *i'* from the upper surface thereof, a wire *i''* extending from this post to a battery *l* located in any convenient position. The end of the casing also supports another binding post *k* to which is attached the wire *k'*, this wire extending to a bell *m*, or like device and from thence to the opposite pole of the battery *l* from that to which the wire *i''* is attached. This binding post is insulated, as at *k''*, from the metal composing the top of the tubular casing that is a good conductor for electricity. The binding post, *k*, or a part secured thereto, projects downward through the insulating material, as shown at *k'''*, and on the lower end is provided an outturned foot forming a contact *k''''* projecting in the path of movement of the lever *c*, this lever and the fulcrum *g* also being good conductors of electricity.

The operation of the device is as follows: When the water in the case *a* has reached a predetermined level the float *d* buoyed therein is borne against one of the baskets *b* tilting the lever and causing the end to bear against the contact *k''''* on the lower part of the binding post *k*. This movement of the parts closes the circuit, thus sounding the alarm *m* located at any desired distance from the boiler. This movement of the lever also draws the valve *h* from its seat in the passage *e'* and causes the whistle located on the case to be sounded at the same time that the electrical alarm is sounded, provided the stop cock *f* is open.

I claim as my invention—

1. In combination in a water alarm for a steam boiler, a casing adapted to be secured thereto, the baskets depending from a lever, the lever pivoted within the casing, the float or buoy located between the baskets, the contact in the path of movement of the lever, and an electrical circuit including therein an alarm, one pole of the battery being connected to the contact and the other to the casing, all substantially as described.

2. In combination in a water alarm for a

steam boiler, a casing adapted to be secured thereto, the baskets depending from a lever, the float or buoy supported between the baskets, the lever pivoted within the casing, the contact located in the path of movement of the lever, and an electrical circuit including therein an alarm, one pole of the battery being connected to the contact and the other to the casing, the whistle located on the casing, the passage extending from the casing to the whistle and adapted to be opened or closed by the movements of the lever, all substantially as described.

3. In combination in a water alarm for a steam boiler, a casing adapted to be secured thereto, the baskets depending from a lever,

the buoy supported between the baskets, the lever pivoted within the casing, the contact located in the path of movement of the lever, an electrical circuit including therein an alarm, one pole of the battery being connected to the contact and the other to the casing, the whistle located on the casing, the passage extending from the casing to the whistle and adapted to be opened or closed by the movements of the lever, and the stop cock located within the passage, all substantially as described. 20 25

CHARLES A. HATCH.
